UNITED STATES PATENT OFFICE.

WILLIAM JOHN STUART, OF PORTLAND, CONNECTICUT.

TELEPHONE ATTACHMENT.

1,084,239.

Specification of Letters Patent. Patented Jan. 13, 1914.

Application filed May 8, 1913. Serial No. 766,329.

To all whom it may concern:

Be it known that I, WILLIAM JOHN STUART, a citizen of the United States of America, residing at Portland, in the county of Middlesex and State of Connecticut, have invented new and useful Improvements in Telephone Attachments, of which the following is a specification.

My invention relates to a stand adapted to be secured to a desk telephone for the reception of the receiver when taken down from its hook, and serves to hold the receiver in adjustable position near the ear of the person using the phone, whereby both his hands may be free.

I am well aware that devices of this general nature have hitherto been invented and patented. These devices, however, in so far as I am aware, are all rather intricate and complex in structure, are, therefore, necessarily expensive, and, moreover, have, in addition, the disadvantage that they are not hung to the telephone in a balanced manner, thereby always having a tendency to upset the telephone whose base is not ordinarily of a large diameter.

Among the important advantages of my new and improved device and aside from its cheapness, simplicity, and ready adjustability, I desire to particularly point out that the device is self-balancing (so that one part thereof counter-balances another part) and therefore has no tendency to upset the telephone, but, on the other hand, makes for its stability.

I have illustrated my new device in the following drawings, in which:

Figure 1 is a front view of the telephone with the device attached in a slightly distorted position. Fig. 2 is a side view of the telephone with the device attached in its proper position. Fig. 3 is a front view of the telephone with the device attached and the receiver on the hook. Figs. 4, 5 and 6, each illustrate details of construction of the clutch-member forming an important part of my invention.

The telephone, broadly, is designated by the reference letter *a*. Upon the telephone is mounted a clamping bracket *b* adjusted in an obvious manner by the turn-buckle *c*. This bracket carries a stand *d* loosely supported on the pin *s* in a vertical aperture in the member *b*, as shown in Fig. 1. The upper end of the bracket is provided with a socket *m* in which is inserted the shank por-

tion *p* of the clutch device, to be herein-after fully described, this shank being adjustable vertically in socket *m* through the medium of the set-screw *l*. The clutch proper comprises (see Figs. 4, 5, and 6) a blade *d'*, upon the shank *p*, having a rounded or cam edge *d''*. Embracing this blade and pivoted thereto at *f* is a U-shaped clutch-member *e* having an inclined inner face *k*, as clearly shown in the drawings. Slidably but removably mounted between this face *k* and the upper face *n* of the blade-member *d'* is the rod *g* carrying at its upper end the cylindrical receptacle *h* adapted to receive the telephone receiver. When in operative position, my device is situated as shown in Fig. 2 so that the portions *b*, *d*, and *e* thereof lie directly behind the mouth-piece of the telephone while the arm *g* is extended to hold the receiver in a position substantially in front of the receiver. This arrangement makes the device perfectly self-balancing and obviates any tendency to upset such as would ordinarily arise where some other structure was hung to the telephone proper.

The operation will be clear upon an inspection of the drawings. It is, however, desirable to point out the action of the clutch, inasmuch as this is an important feature of the invention. In the position shown in Figs. 1, 2, and 6, the arm *g* binds between the two faces *n* and *k* (Fig. 6) owing to the downward force exerted at its upper end by the telephone receiver or by the weight of the arm *g* which in operative position is extended as shown in Fig. 1. To drop the arm *g* and the receiver *h* back into the position shown in Fig. 3 in which it is entirely behind the mouth-piece of the telephone and completely out of the way, it is only necessary to tilt the arm *g* by raising its upper end whereupon the face *k* takes the position shown in Fig. 4 in which position it is opposite the cutaway portion *d''* of the blade *d'* and the arm *g* may readily slide down to the position shown in Fig. 3.

It is to be particularly noted that all parts of this device, the stand *b*, the upright *d*, the clutch *d'* and *e*, and the rod *g*, may be very readily disassembled and any part thereof may therefore be easily replaced or made and sold separately.

While I have described one specific form of my device, it is to be understood that many modifications thereof might be readily

made without departing from the invention, the scope of which is more clearly defined by the claims hereto appended.

What I claim, is,—

- 5 1. A counterbalanced telephone receiver, comprising a member attached to the telephone, an arm slideable on said member, connection between the arm and the member, whereby when the arm is in one position it is bound thereto and when it is tilted it may slide freely upon said member, and a socket for the telephone receiver upon said arm.
- 10

2. In an adjustable telephone receiver holder, a support, a clutch comprising a supporting blade having a cam portion, a U-shaped member embracing the blade and pivoted thereto, and a rod between the blade and the said U-shaped member, said rod carrying at its upper end a telephone receiver seat. 15

WILLIAM JOHN STUART.
